POWDER PUFF

Mary Stevens Landsman, Chicago, Ill., assignor
to The Pupek Company, Chicago, Ill., a corpora-
tion of Illinois

Application June 8, 1939, Serial No. 278,035

7 Claims. (Cl. 132—78.5)

This invention relates to powder puffs for applying powder and like substances as well understood in the art.

One of the main objects of the invention is to provide an improved powder puff in which there is an opening through which powder may be introduced into the puff and provided with suitable closure means for the opening.

Another and more specific object of the invention is to provide an improved powder puff having opposite sides, at least one of which is formed of suitable material for applying the powder or like substance to the desired surface, there being a suitable pad between the sides of the puff and the side opposite the side for applying the powder having a bushing or the like defining an opening through the adjacent side of the puff and also through the pad, so that the powder may be introduced not only into the puff but between the pad and the side of the puff for applying the powder and uniformly distributed over the inner surface of such side.

Another object of the invention is to provide in an improved powder puff of the character set forth a bushing which not only defines an opening through which the powder is introduced through the adjacent side of the puff and through the pad and into the puff between the pad and the opposite side of the puff, but which also serves to hold the pad to the side of the puff in which the bushing is secured to facilitate introduction of the powder in the manner set forth and distribution of the same over the inner surface of the side for applying the powder.

It is also an object of the invention to provide a powder puff of the character described of simple and inexpensive construction and into which the powder may be conveniently introduced; also a device composed of few parts and adapted to be made up expeditiously.

Further objects and advantages of the invention will appear from the following detailed description taken in connection with the accompanying drawing in which:

Fig. 1 is a back elevation of a powder puff embodying the present invention;

Figure 2 is a section taken on the line 2—2 of Figure 1;

Figure 3 is a front elevation partly broken away to reveal the internal pad or cushion and the inner end of the pad retaining and opening defining bushing;

Figure 4 is a fragmentary back elevation of another powder puff embodying the present in-

vention and showing another form of pad retaining and opening defining bushing; and

Figure 5 is a fragmentary section taken on the line 5—5 of Figure 4.

Referring now in detail to the drawing, the powder puff shown in Figures 1 to 3, inclusive, comprises two opposite sides 5 and 6 formed of suitable material, preferably a soft fabric such as velvet, velour, plush-like material or the like. The side 6 constitutes the side for applying the powder to the desired surface, and at least this side preferably has a pile surface 7 which is presented outwardly, as shown. The inner surface of the side 6 may be smooth or of the usual character, and the opposite or back side 5 may be of similar character.

The marginal edges of the sides 5 and 6 are secured together by stitching indicated at 10. In the particular embodiment of the invention shown in the drawing the stitching 10 is internally disposed to form an internal annular seam between the margins of the sides 5 and 6. This may be accomplished by stitching the sides 5 and 6 together with their outer sides presented inwardly and extending the stitching 10 short of the full distance around the periphery of the pad. This leaves an opening through which the puff may be turned inside out to present the pile surfaces outwardly, as shown. The relatively small opening indicated at 12 through which the puff is thus turned inside out may then be stitched closed, or it may be glued or closed in any other suitable or desired manner.

Prior to stitching the opposite sides 5 and 6 of the puff together as described, a pad or cushion 15 is applied to what is to constitute the inner surface of the back side 5. This pad 15 may be formed of cotton batting or other suitable pad material, and it may be cut to the desired form, and is provided with a central opening 16 which registers with a corresponding central opening 17 in the back side 5 of the puff.

The tubular bushing 18 formed of rubber or other suitable material is inserted through the registering openings 16 and 17 into the position 45 shown in Figure 2. This bushing 18 has an integral flexible outer flange 20 which cooperates adjacent the opening 17 with what is to constitute the outer surface of the back side 5, and also an inner flange 21 which cooperates adjacent the inner end of the opening 16 with what is to constitute the inner side of the pad 15. The bushing 18 has a filler opening 22 through which the powder or the like is introduced through the back side 5 and pad 15 and into uniformly 50

distributed relation between the pad 15 and the inner surface of the front side of the puff. The bushing 18 also, by the construction described, serves to hold the pad or cushion 15 to the back side 5 of the puff to facilitate introduction of the powder and distribution of the same over the inner surface of the front side 6.

It is to be understood that the pad 15 and bushing 18 are secured to the back side 5 before stitching 10 it to the front side 6, and that in stitching the sides together the pad 15 and bushing 18 will be externally disposed. Upon turning the puff inside out to dispose the stitching 18 internally, the pad 15 and bushing 18 are disposed internally 15 as shown in Figure 2.

The filler opening 22 is provided with closure means in the form of a removable stopper or plug 24 formed of rubber or other resilient material. The resilient character of the bushing 18 20 and stopper 24 holds the stopper firmly in place and, at the same time, permits ready removal of the stopper for the purpose of introducing powder into the puff.

The stopper 24 may be provided at its outer 25 end with an integral finger piece as shown at 24', or this finger piece may be omitted. The inner flange 21 is preferably of considerably larger diameter than the outer flange 20, but this too may vary. The outer periphery of the flange 20 30 which is free of the back side 5 may be provided with an external annular bead as shown at 20', and it may also be provided with an inner annular bead of similar form for cooperation with the back side 5 of the puff.

35 The periphery of the puff is provided with a fabric tab 25 for holding the puff. This tab 25 may, of course, be omitted, and the puff may, if desired, be provided with a peripheral beading, or it may be formed otherwise as desired. 40 The puff is shown of circular form, but this too may vary within the scope of the present invention.

In the modification shown in Figures 4 and 5, the bushing 18' is formed of rubber or other resilient material as in the preceding embodiment 45 of the invention. Also, as in the preceding embodiment, this bushing defines a filler opening through the back side 5' and through the pad 15' for introduction of the powder into the puff, 50 as before. However, the separate stopper or closure 24 of the preceding embodiment of the invention is eliminated. This is accomplished by pleating the outer part of the bushing 18' as shown at 28. This pleating may begin inwardly—for 55 example, about half way between the thickness of the pad 15'—or it may be disposed at the outer end of the filler opening terminating in a straight or whirling pleated rosette of the rubber or other resilient material, of which the bushing 60 is made. The inner flange 21' remains the same.

The bushing shown in Figures 4 and 5 performs the functions of the bushing shown in Figures 1 to 3, inclusive, and, in addition, the pleated 65 form of its outer end makes it self-closing. The bushing 18' may be opened by drawing the sides of the outer part of the bushing apart adjacent the pleating 28 to open the filler opening for introduction of the powder and, upon being released, the pleated outer end 28 of the bushing 70 will spring back to its normal form, thereby closing the filler opening of the puff.

In the use of the puff the resilient bushing and, where a stopper is employed, the stopper in conjunction with such bushing seals the powder in 75

the puff and prevents it from coming out except in the desired direction or along the side which is patted against the surface to which the powder is to be applied. It is to be understood that the side 6 is porous or of a character to permit the powder to pass therethrough; for instance, by patting against the surface to which the powder is to be applied. While the bushing means is described as being secured or placed in the side 5 before securing the sides 5 and 6 of the puff together, it is to be understood that the bushing means may be put in after securing the sides of the puff together.

The disposition of the filler opening defined by the bushing means in the center of the side 5 of the puff provides for uniform distribution of the powder between the side 6 and the pad 15. Moreover, the disposition of the bushing and plug at the center of one side of the puff places the same where the filler opening does not tend to be opened or the plug released by patting the puff in applying the powder. In fact, with the fingers on the back of the puff, the patting action tends to keep the closure tight.

The side 5 will be preferably formed of an impervious material, but this may, of course, vary within the scope of the present invention.

I do not intend to be limited to the precise details shown or described.

I claim:

1. A powder puff comprising a front side of material adapted for applying powder to the desired surface, a back side secured marginally to said front side, a pad between said back and front sides, and a bushing extending through said pad and said back side and defining a filler opening for the introduction of powder into place between said pad and the inner surface of said front side.

2. A powder puff comprising a front side of material adapted for applying powder to the desired surface, a back side secured marginally to said front side, a pad between said back and front sides, and a bushing extending through said pad and said back side and defining a filler opening for the introduction of powder into place between said pad and the inner surface of said front side, said bushing having a flange at its inner end and cooperating with the back side to hold said pad to the back side of the puff.

3. A powder puff comprising a front side of soft fabric adapted for applying powder to the desired surface, a back side secured marginally to said front side by an internal seam and having an opening therethrough, a pad disposed between said back and front sides and having an opening in register with the opening in said back side, and a resilient bushing extending through said registering openings and defining a filler opening for the introduction of powder into place between said pad and the inner surface of said front side, said bushing cooperating at its outer end with the outer surface of said back side and having a flange at its inner end cooperating with the forwardly disposed side of the pad to hold the pad to the back side of the puff.

4. A powder puff comprising a front side of material adapted for applying powder to the desired surface, a back side secured marginally to said front side, a pad between said back and front sides, a resilient bushing extending through said pad and said back side and defining a filler opening for the introduction of powder into place between said pad and the inner surface of said front side, said bushing having a flange at its

inner end and cooperating with said back side to hold said pad to the back side of the puff, and a resilient stopper for said filler opening.

5. A powder puff comprising a front side of material adapted for applying powder to the desired surface, a back side secured marginally to said front side, a pad between said back and front sides, and a resilient bushing extending through said pad and said back side and defining a filler opening for the introduction of powder into place between said pad and the inner surface of said front side, said bushing having a flange at its inner end for holding said pad to the back side of the puff and being pleated at its outer end to cooperate with said back side and to form a self-closure for said filler opening.

6. A powder puff comprising a front side of material adapted for applying powder to the desired surface, a back side secured marginally to said front side, a pad between said back and front sides, and a filler opening defining member extending into the puff and defining a filler opening for the introduction of powder into place be-

tween said pad and the inner surface of said front side, said filler opening defining member being disposed to hold said pad away from the front side of the puff for the entry and distribution of the powder between the pad and the inner surface of the front side of the puff. 5

7. A powder puff comprising a front side of material adapted for applying powder to the desired surface, a back side secured to said front side, a pad between said back and front sides, 10 and a resilient filler opening defining member extending into the puff and defining a filler opening for the introduction of powder into place between said pad and the inner surface of said front side, said resilient filler opening defining 15 member having a resilient portion disposed between the inner surface of said front side and said pad to hold said pad away from the front side and to the back side of the puff for the entry and distribution of the powder between the pad 20 and the inner surface of the front side of the puff.
